UNITED STATES PATENT OFFICE.

MYRON B. NUTE, OF CHICAGO, ILLINOIS.

WINDOW-VENTILATOR.

1,170,559.

Specification of Letters Patent.

Patented Feb. 8, 1916.

Application filed November 11, 1912, Serial No. 730,610. Renewed December 20, 1915. Serial No. 67,943.

To all whom it may concern:

Be it known that I, MYRON B. NUTE, a citizen of the United States, residing at Chicago, in the county of Cook and State of Illinois, have invented certain new and useful Improvements in Window-Ventilators, of which the following is a specification.

My invention relates to improvements in window ventilators, and more particularly in that class of ventilators which are adapted to deflect the air from a window upwardly toward the ceiling of the ventilated room.

One of the objects of my invention is to provide, an efficient simple, easily to be attached, and removed, adjustable window ventilator which shall be cheap of construction and effective in operation.

Another, and more specific, object of my invention is to make the device of a light weather-proof material, of sufficient rigidity and strength to withstand the work and wear imposed upon it, by daily use, and yet inexpensive in character.

Other and further objects of my invention will become readily apparent, to persons skilled in the art, from a consideration of the following description when taken in conjunction with the drawings, wherein:—

Figure 1 is a view of an interior of a room, or apartment, showing the ventilator in perspective, as it is applied to a window; Fig. 2 shows the device detached, with the hinged angular end pieces open flat, and showing the same side as that seen in Fig. 1; Fig. 3 is a similar view showing the other, or outside of the device; Fig. 4 is a section taken on line 4—4 of Fig. 2; Fig. 5 is an enlarged section taken on line 5—5 of Fig. 2; Fig. 6 is an enlarged section taken on line 6—6 of Fig. 2.

In all the views the same reference characters are employed to designate similar parts.

10 is the inner wall of an apartment, or room, provided with a window, of which 11, is the casing.

12 is a vertically movable sash and 13 is the base portion of the casing.

In Fig. 1 the ventilator is shown in such position that the sash may be vertically moved without disturbing the ventilator, and in this figure the sash is raised higher

than it would be when in proper operative position, the view thus showing more clearly the sash and its relation to the ventilator.

The ventilator consists, essentially, of two substantially duplicate parts 14 and 15, each part terminating in a triangular piece 16, which is hingedly joined, by proper articulation between the parts, in a substantial vertical line, to its respective main portions 14 and 15. The members, 14 and 15, are movably secured together in such way that they may be longitudinally extended and contracted for the purpose of adjusting the length of the device to windows of varying width. As heretofore stated, a cheap and efficient device may be provided by the use of corrugated straw boards or other like fiber material, and in the making of the device from such material it is advisable, as hereafter described, to protect the raw edges by binding them with a suitable paper or fabric tape. It is therefore advisable that the edges of the overlapping boards be left free and unmutilated and to this end my invention contemplates the provision of slots 17 and 18 in one of the members, as in the interior member 14, of the drawing, and cleats 19 and 20, the narrow portions 21 and 22 of the cleats respectively, are adapted for sliding movement in slots 17 and 18, respectively, and the cleats are held to the outer member, 15, by means of screws 23. By this means the members 14 and 15 may be moved longitudinally to the extent permissible by the slots 17 and 18 and the cleats 19 and 20. For best construction and operation I provide sufficient friction between the cleats and the contracting members, so that the parts will remain in the positions to which they have been adjusted to the end that it may be freely handled without disturbing the longitudinal adjustment of the device as a whole. The members 14 and 15 may conveniently be made of corrugated straw boards, or other like fibrous material, comprising an interior, corrugated member 24, and the outer flat members 25—25 secured thereto, as by glue or the like. After the members 14 and 15 have been cut from the material, each of the members are bound around the edges by sufficiently flexible stout fibrous

material, such as paper, fabric tape, or the like, and other raw edges are protected in like manner as shown at 26. The angular end members 16, are connected to their respective major portions or members, 14 and 15, by a suitable articulate joint, represented by 27, whereby angular motion may occur between the parts in a substantially vertical plane. When the device is made of 10 the material which I have heretofore described, the articulate connection between the parts 16 and their respective major portions, may be made by placing a narrow, thin, straight edge over the line 27 and by 15 applying pressure to the straight edge thereby providing a kerf in the parts 25 and the intermediate corrugated member 24, whereby to provide an articulate hinge upon which the part 16 may be moved. 20 For the purpose of attaching the device to the sides of the window casing I provide elongated slots 29, made in and near the top of each of the angular pieces 16, for attaching co-operation with the screw eyes 30, 25 that may be placed in the sides of the window casing 11, as a means for holding the device in position.

In applying the device to the window, the major portions, 14 and 15 are longitudinally moved until the end pieces 16 are separated a distance equal to the distance between the side parts 11 of the window casing. Then each part 16 is bent inwardly 35 slightly more than at right angles from their major portions to which they are connected. In applying the device, the screw eye 30 is turned so that the eye portion is substantially parallel with the longest part of the slot 29. The slots 29 are then slipped 40 over the screw eyes and the screw eyes are then turned to an extent equal to about 90° as shown in Fig. 6, whereby the device will be held in its proper position in the window.

45 While I have herein described a special material, of which the device may well be made, and which I consider to be the preferable material for the purpose, yet my invention is not to be limited to the exclusive 50 use of such materials.

Fig. 3 shows the device as it would appear when made of wood, or the like, in which event the parts 16 and 14 and 15, respectively, are joined by hinges 31 that may 55 be attached by means of screws and in which event it will not be necessary to bind

the edges with tape, as heretofore described.

When the device is made of paste-board, the outside surfaces, including the binding 60 is preferably treated with a water-proofing material, such as a suitable varnish, or the like, so as to render it non-absorbent of moisture to give it sufficient rigidity, and to add to its sanitary qualities. 65

While my device is intended for permanent use, the ease with which it may be attached and removed, renders it convenient for intermittent use in bed rooms, or other sleeping apartments, where it may be 70 frequently applied and removed, and being light in weight it may be readily handled with but little exertion.

In the operation of the device, the window 12 is raised an extent equal only to 75 about one half the vertical height of the deflector, so that when the incoming air strikes the inclined surfaces formed by the parts 14 and 15, it is thereby upwardly deflected to a region near the top of the room, 80 or near the ceiling, so that it may mingle with the warmer air, of the apartment, or room, before it descends to the breathing line, and comes in contact with the persons therein. 85

While I have herein described a single embodiment of my invention, for the purpose of clear disclosure, it is apparent to persons skilled in the art that many changes may be made without departing from the 90 spirit and scope of the appended claim.

What I claim is:

A window ventilator comprising two lapped longitudinally movable boards, end members secured to each of said movable boards, one of the movable members having near its center, long narrow slots, elongated cleats of a width greater than that of the slots overlying the outer edges of the slotted boards and extending through the 100 slots, and clips fastened near the outer ends of the said cleats and joining them with the imperforate member, thereby providing sliding connections between the two members. 105

In testimony whereof I hereunto set my hand in the presence of two witnesses.

MYRON B. NUTE.

In the presence of—
W. LINN ALLEN,
MARY F. ALLEN.
